UNITED STATES PATENT OFFICE.

HARRY S. HART, OF CHICAGO, ILLINOIS.

HOPPER-DUMP-CAR CONSTRUCTION.

1,300,959.

Specification of Letters Patent. Patented Apr. 15, 1919.

Application filed October 21, 1915. Serial No. 258,991.

To all whom it may concern:

Be it known that I, HARRY S. HART, a citizen of the United States, residing at Chicago, in the county of Cook and State of Illinois, have invented certain new and useful Improvements in Hopper-Dump-Car Constructions, of which the following is a specification.

This invention relates to dump cars.

10 The object of this invention is to simplify and improve dump car constructions in a novel manner to increase the capacity thereof and at the same time retain the self-cleaning feature.

15 This and other objects are accomplished by means of the arrangement disclosed by the accompanying sheets of drawings, in which—

Figure 1 is a fragmentary side elevation of 20 a railway dump car embodying my invention;

Fig. 2 is a fragmentary plan view of the same car;

Fig. 3 is a transverse sectional view of the 25 same dump car taken over one of the trucks; and,

Fig. 4 is a transverse sectional view of the same car taken between the trucks.

It is a well recognized fact that it is of 30 vital importance to increase the carrying capacity of railway cars, and especially dump cars for carrying coal and other dumpable materials, in view of the great demand as a result of traffic conditions.

35 In one well known type of dump car in which the floor intermediate the trucks is composed of a plurality of hopper portions, each including a plurality of doors hinged transversely of the car and swinging toward 40 and from each other to closed and opened positions, respectively, and in which the floor portion at each end over the trucks includes a long sloping member extending from the end of the car downwardly toward the trans- 45 verse center line of the car, it is found that the capacity can be effectively increased by changing the floor construction over the trucks.

Referring to the figures of the drawings, 50 it will be noted that I have shown a dump car including sides 10, ends 11 and a floor, the floor portions over the trucks being of A-shaped construction in which the apex 12 of the A is located over the center sill 13, the 55 sloping members 14 of the A-shaped portion extending downwardly and outwardly to-

ward the sides of the car. These sloping floor members 14 preferably are stationary and connected to the under frame to thereby increase the stiffness and rigidity of the car 60 structure. The discharge openings at the lower ends of the floor portions 14 normally are closed by side dump doors 15 which preferably are pivotally connected at 16 along the lower edges of the sides 10 of the car, 65 the swinging edges of the doors 15 when in closed position forming a tight seal with the lower edges of the floor members 14. The dump doors 15 may be provided with any suitable operating mechanism including operating shafts 17, preferably carried by the doors 15, and also chains 18, which connect the shafts with the stationary floor portions 14.

The floor intermediate the trucks is at a 70 lower level than the floor portions over the trucks and includes a plurality of transversely arranged hoppers 19 formed by transversely extending shedding members 20, there being transversely arranged hoppers 19 on both sides of the longitudinal center of the car, the longitudinal division of the car being formed by shedding means 21. Each of the transversely arranged hoppers 19 has its floor portion composed in part by 75 a plurality of doors 22 hinged transversely of the car and swinging toward and from each other to closed and opened positions, respectively. Leading from the extreme doors 22 nearest the ends of the car are 80 sloping floor members 23 which extend to the apex 12 of the floor portions over the trucks. In cars heretofore built the sloping floor portion 23 is continued in the same 85 plane to the end 11 of the car. It is apparent, therefore, that by providing the floor construction over the trucks, as shown in this application, the carrying capacity of the dump car is greatly increased and at the same time the self-cleaning feature is retained. When the side dump doors 15 are 90 opened, it will be appreciated that all of the dumpable material over the trucks will be discharged to either side of the car, and when the transversely arranged dump doors 15 are opened, the remaining dumpable material in the car will be discharged intermediate the trucks, all of the floor portions being slanting or movable in a manner such that the car will completely discharge its 100 load upon opening of the doors. The transversely arranged dump doors may be pro-

vided with any suitable operating mechanism 24.

It is my intention to cover all modifications of the invention falling within the 5 spirit and scope of the following claims.

I claim:

1. A car of the class described having 10 sides, ends and a floor, the floor over the trucks comprising portions sloping downwardly and outwardly toward the sides of the car, the floor between the trucks comprising a plurality of doors hinged transversely of the car and swinging toward and from each other to closed and opened positions, respectively.

2. A car of the class described having 20 sides, ends and a floor, the floor over the trucks comprising portions sloping downwardly and outwardly toward the sides of the car, the floor between the trucks being at a lower level than the floor over the trucks and comprising a plurality of doors hinged transversely of the car and swinging toward and from each other to closed and 25 opened positions, respectively.

3. A car of the class described having 30 sides, ends and a floor, the floor over the trucks comprising portions sloping downwardly and outwardly toward the sides of the car, the floor between the trucks comprising a plurality of oppositely arranged transversely mounted swinging doors.

4. A car of the class described having 35 sides, ends and a floor, the floor over the trucks comprising stationary portions sloping downwardly and outwardly toward the sides of the car, the floor between the trucks comprising a series of oppositely arranged

transversely mounted associated swinging hopper doors.

5. A car of the class described having 40 sides, ends and a floor, the floor over the trucks comprising portions sloping downwardly and outwardly toward the sides of the car, the floor between the trucks comprising a plurality of doors hinged transversely of the car and swinging toward and from each other to closed and opened positions, respectively, and door operating mechanism for said doors.

6. A car of the class described having 45 sides, ends and a floor, the floor over the trucks comprising stationary portions sloping downwardly and outwardly toward the sides of the car, side dump doors whereby 50 the load over the trucks may be dumped to the sides of the car, the floor between the trucks comprising a plurality of doors hinged transversely of the car and swinging toward and from each other to closed and 55 opened positions, respectively.

7. A car of the class described having 60 sides, ends and a floor, the floor over the trucks comprising stationary portions sloping downwardly and outwardly toward the sides of the car, side dump doors whereby 65 the load over the trucks may be dumped to the sides of the car, the floor between the trucks comprising a plurality of doors hinged transversely of the car and swinging toward and from each other to closed and 70 opened positions, respectively, and door operating mechanism for said doors.

Signed at Chicago, Illinois, this 18th day of October, 1918.

HARRY S. HART.
